CONVEYER-PROPELLED SUPPLY TRUCK
FOR USE WITH SHAKING CONVEYERSJoseph F. Joy, Pittsburgh, Pa., assignor to Joy
Manufacturing Company, Pittsburgh, Pa., a
corporation of Pennsylvania

Application February 25, 1949, Serial No. 78,274

5 Claims. (Cl. 198—220)

1

This invention relates to a conveyor-propelled supply truck for use with shaking conveyors of the type employed in mining.

Shaker conveyors are extensively employed in mines, and particularly in mines where low head room makes other means of transportation difficult. Such conveyors extend from the actual point at which mining operations are being carried on to a suitable car loading or discharge point, and accordingly extend along a path over which implements, roof supports, and the like must be transported. These articles, being heavy and difficult to handle where the roof is low, are commonly placed on supply trucks which are moved along the conveyor pan line. The trucks may be moved manually. They may be towed by lines, or may be caused to traverse the pan line automatically by motion derived from the pan line itself. Such trucks may be utilized in the transportation of passengers also.

A primary object of this invention is the provision of an improved truck which may be caused to move between the working face and some relatively remote point, and to convey a load, as, for example, mine props or the like, toward the working face, and to carry out items which it is desired to remove from the working face. A further and more specific object of the invention is the provision of an improved truck of such character, having supporting wheels adapted to be supported upon the edges of the conveyor trough and to move therealong, and having improved means for effecting movement along the conveyor trough. Another object of the invention is to provide an improved truck of the character mentioned which will automatically return to its starting point remote from the working face unless either detained positively at the working face or rendered operative, under control means carried thereby, to travel toward the working face. Another object of the invention is to provide an improved feeding means for a truck of the character described having improved means whereby the same may be rendered inoperative at will. Still another object of the invention is to provide an improved feeding means for a truck of the character described having means by which it may be automatically rendered inoperative when it arrives at a desired point, by engagement with abutment means arranged at such point. Still a further object of the invention is to provide an improved truck of the character mentioned having improved feeding means frictionally engageable at will with the bottoms of the flanges at the sides of the pan line. Still another object of the invention is to

2

provide an improved truck of the character described having improved means for conveying a load without requiring excessive height in the mine passages. Other objects and advantages of the invention will hereinafter more fully appear.

In the accompanying drawings, in which for purposes of illustration a preferred embodiment of my invention has been shown,

Fig. 1 is a top plan view showing a supply truck constructed in accordance with my invention mounted upon a reciprocating conveyor trough.

Fig. 2 is a side elevation of the supply truck and of the portion of the shaker conveyor pan line shown in Fig. 1.

Fig. 3 is a vertical transverse section on an enlarged scale, the section being taken on the planes of the line 3—3 of Fig. 2.

Fig. 4 is an enlarged fragmentary side elevational view, with parts broken away, showing one of the intermittent gripping devices employed in effecting movement of the truck in one direction along the pan line.

Now referring more particularly to the drawings, there may be noted at 10 a portion of a shaker conveyor trough or pan line. This is herein shown as supported not by the customary ball frames but by means of rubber tired wheels 11, 11, each journaled upon a suitable axle 12 carried by an appropriately reinforced, transversely extending support member 13, to which a pan section is connected, desirably at or adjacent one end of the latter, and the underlying support or frame 13 has eyes 14 which are adapted to be connected to corresponding eyes on an adjacent pan section by the extension of bolts therethrough in a manner readily understood by those familiar with this art.

The pan line or shaker conveyor trough 10 may be reciprocated by any suitable means. Such shaker conveyor drives are well known to the art, and as the details of the pan line reciprocating mechanism do not per se form a part of my invention, they are not illustrated. It will be understood, however, that the pan line will be alternately moved outwardly away from the working face at a relatively slow speed, and moved inwardly at a relatively higher speed whereby material carried on the pan line will move with the latter on its outward movements but will have the latter slide beneath it during the more rapid inward movements, with a result that the material will be moved in a series of short steps progressively from the place of its deposit on the pan line to the point of discharge of the latter.

The pan line trough or conveyor pan sections

10 are provided with outturned, rounded flanges 16 which constitute rails or guides along which the truck in which my invention is incorporated is adapted to move.

The supply car is generally designated 20. It is supported by wheels 21—two, as illustrated, at either end thereof, the wheels being supported by suitable bearings 22 on axle elements 23. The axle elements are fixed between angle plates 24 and spaced upright plate portions 25 which are parts of inverted U-shaped frame or bracing elements 26, herein shown as of built up construction and provided with downwardly sloping opposite ends 27. The plates 24 and bracing elements 26 are herein shown as welded together. The upright plate portions 25 are secured at their lower, inner ends as by welding to angle irons or other suitable sill or main frame members 28 extending longitudinally of the truck. A suitably shaped top and cover and reinforcing member 29 extends lengthwise between the frame or bracing elements 26 and is suitably secured to them. This, with its angularly related bottom portions 30 secured to the ends 27, forms the inner side walls and bottoms of storage compartments later mentioned. Fixed to the outer ends of the downwardly sloping ends 27 of the frame elements 26 are the vertical legs 32 of inverted U-shaped frames 33 which have hinge pin receiving openings 34 at their opposite top corners, by means of which there may be provided bearings for the pivot rods of side covers 35 for upright side compartments 36 of the truck body located outwardly of the upright plate portions 25. These side covers are provided between their ends with pivot mountings 37 for lock bars 38 which are tiltable by an operating portion 39 so as to release them from locking engagement with sockets 40 provided by keeper elements 41 welded or otherwise suitably held to the uprights 32. It will be noted that the side compartments 36 are adapted, since they extend at their bottoms down below the axles of the supporting wheels 21, to carry a substantial load of mine props or other articles without having any of the load piled a substantial distance above the top of the truck proper. The truck can, of course, where headroom permits, be also loaded by superimposing upon its top additional items to be moved. However, it is noteworthy that the main enclosed load carrying chambers 36 are disposed to the outside of the conveyor trough or pan line and extend actually below the bottom of the latter.

I have found that with an arrangement such as has been so far described the truck, if arranged on the shaker conveyor pan line at a point between the ends thereof, will, if the pan line is reciprocated in the manner above described, move promptly out towards the outer end of the pan line, that is, away from the working face. This I attribute to the fact that during the relatively slow outward movements of the flanges of the pan line the wheels 21 may roll outwardly, whereas during the rapid inward movement of the pan line beneath the wheels, there will be initiated, as it were, a spinning of the wheels in a direction to cause the supply truck to roll away from the working face. In other words, the wheels during the relatively rapid inward movement of the pan line beneath them have two things happen; the wheels are caused to tend to rotate in the direction they would rotate in carrying the truck out of the mine, and, after the velocity of the pan line gets

such as to cause a slippage relative to the wheels and beneath the latter, there is a bodily relative movement of the pan line relative to the truck inwardly, so that only in the event that there should be a corresponding outward movement of the pan line relative to the truck would there be no net outward movement of the truck at the end of a complete cycle of reciprocation. During the relatively slow outward movement of the pan line the relative velocities are not great enough to cause slippage of the pan line relative to the wheels, and instead the wheels, which have a tendency to roll outwardly because of the rotative movement previously imparted to them, do roll along the relatively outwardly moving pan line with a result that there is a progressive outward movement of the truck as a whole. The explanation I have given may unduly simplify matters, and is to be understood as being merely my best understanding of what takes place, but if the explanation is not wholly correct, this does not derogate from the fact of operativeness and is not to prejudice the invention whose structure is illustrated and described.

25 Since the truck will run out of the mine while the conveyor pan line is reciprocating unless it is prevented from doing so, it will evidently be necessary to provide some means for causing it to move into the mine. This can be done by providing an intermittent grip device movable with the vehicle and engageable with a portion of the pan line, and I have herein illustrated such a device cooperating with the lower sides of the flanges at the outer side edges of the pan line. 30 These intermittent grip devices should possess certain characteristics. It is desirable that they be provided at either side of the vehicle. It is desirable that they be capable of being rendered ineffective at will, and it is also desirable that they be capable of being rendered inoperative automatically upon attainment of the truck to any desired point at which its movement into the mine may be desired to be stopped. It is also desirable that the truck not only have means by which its travel may be automatically interrupted, but further that it have means whereby its reverse movement may be prevented from taking place after the automatic inward feeding means thereof has been rendered inoperative.

35 50 Intermittent grip devices are associated with the truck at points adjacent each wheel thereof. Each includes, pivotally mounted at 43 upon one of the axles 23, between the wheel 21 thereon and the vertical plate 25, a depending arm 44, which is connected pivotally as at 45 at its lower end to a pin 46 mounted in an angle element 47. The angle elements 47 at either side of the truck are considerably elongated and they extend from a point beyond the wheel at the 40 end of the truck which is the front end as the truck moves into the mine, to a point beyond the wheel which is toward the back end of the truck as the latter moves into the mine. It will be appreciated, therefore, since the effective lengths 45 of the arms are the same, that these angle bars or elements 47 have a parallel motion connection with the truck axles. Each element 47 carries, as shown, a pair of upwardly extending, elongated friction members 48, these being transversely curved, and adapted to cooperate with the concave bottom surfaces of the flanges 16, and each arranged in a position generally beneath a truck wheel. The length of the arms 44 or, more mathematically stated, the distance 40 between the axes of the pivots 43 and 45, is such

that when the arms 44 hang vertically there will be no frictional gripping by the members 48 with the bottoms of the flanges 16, but when the arms 44 are swung through even a relatively few degrees out of the vertically depending position, there will be a lifting of the angle elements 47 and the friction members 48 relative to the flanges 16 sufficient to cause a gripping action.

Means is provided for yieldingly forcing the angle elements 47 towards the right in Figs. 2 and 4, so as to cause an automatic gripping between the friction members 48 and the flanges 16 to take place, and this means has associated with it means for rendering it inoperative at will. Noting Figs. 1, 2 and 4, it will be seen that rods 50 are loosely guided at their ends remote from the angle elements 47 in holes 51 in members 52 fixed to the frame of the truck. At their other ends the rods 50 are threaded as at 53, and their threaded ends are secured to members 54 fixedly connected to the angle frames 47. Longitudinal adjustment of the rods 50 with respect to the angle elements 47 may be effected by reason of the threaded connection, and the parts may be held in fixed relation when adjustment has been effected by lock nuts 55. Springs 56 act between members 52 and adjustable nuts 57, carried one on each threaded portion 53, and these springs normally tend to move the rods 50, the members 54, and the angle elements 47 to the right. Were no more mechanism present, the springs would always hold the members 48 in frictional engagement with the flanges 16. Under such circumstances the truck would automatically run into the mine. In order that it may run out of the mine, means is provided for positively moving the arms 44 to vertical positions, thereby to disengage the friction members 48 from the flanges 16. To this end toggle devices 60 are provided at either side of the truck. These devices each consist of an arm 61 mounted on a pivot 62 carried by an ear 63 in fixed relation to the frame of the vehicle, said arm 61 pivotally connected at its other end at 64 to an angled member 65 pivotally connected at 66 to the member 54. The angled members 65 have, as portions thereof, upstanding levers 67, and the upper ends of the levers 67 at the opposite sides of the truck are connected by a cross bar 68 which has projecting handle portions 68A. It will be understood that but one toggle device is provided at either side of the truck. An adjustable stop screw 69 is carried by a shelf-like portion 70 secured to each of the levers 67, and these stop screws are engageable with the members 61 to control the degree that the toggle device 60 can move across center. By the provision of the cross bar 68 the toggle mechanisms at both sides of the truck may be operated simultaneously by means of either handle portion 68A.

Referring to Figures 1 and 2 it will be observed that one angle element 47 has at its end away from its associated toggle mechanism an outwardly directed arm 71, which is adapted to engage a boss 72 formed on a column or jack 73 which may be located alongside the pan line 10 at any desired point. When the truck in its movements toward the face reaches the position of the column 73, the arm 71 will engage the abutment 72 and thrust the angle member 47 to which the arm 71 is connected longitudinally of the truck and move the friction member 48 out of gripping relation to the flange 16, compressing the spring 56 as necessary. The other angle member will be similarly moved, and its friction

member will also be disengaged. Thus inward travel toward the face will be interrupted; and to hold the truck stationary and to prevent outward travel thereof, the truck may desirably be provided with laterally spaced brackets 75 having a cross pin 76 engageable by a releasable latch member 77 supported on a manually rotated shaft 78 at the lower end of the column 73. A handle 79 is provided for releasing the latch when desired and the latch has a sloping nose 80 so that the pin 76 may lift it, and it has a shoulder or short arm 81 for preventing the latch from dropping down too low at its free end. Evidently the truck may be stopped at any desired point simply by properly positioning the jack 73. Platforms 82 are provided, one at each side of the control end of the truck; and a miner can, by the use of these, ride in a position in which he can reach the control handles 68A.

It will be evident from what has been said that the truck will run out of the mine if it is not held in position after the levers 67 have been moved to the position shown in Fig. 4, and the engagement of the arm 71 with the abutment 72 in fact compresses the springs 56 sufficiently to move the pivots 66 far enough to the left relative to the truck to permit the toggles to move across center and lock the friction grip devices in inoperative position.

The mode of operation of the invention as so far described will be readily understood from what has been said. Let it be assumed that the vehicle is at the point from which it is desired to transport a load of material to the working face, and that it has been loaded, and that the side doors to the compartments 36 have been latched in closed position. The miner will then throw the levers 67 from the position shown in Fig. 4 to that shown in Fig. 2. This will permit the springs 56 to cause the friction gripping devices to be moved into frictional contact with the lower surfaces of the flanges 16. During the movement to the right—inward movement—of the pan line, the friction elements 48 will be caused to grip the flanges 16 tightly and the truck will therefore be moved inward a certain distance. When the opposite movement of the pan line occurs, the gripping will be released and the pan line will move between the then freely rotatable wheels 21. On the next inward thrust of the pan line, gripping will again occur and a further movement of the truck in an inward direction will be effected. This process will be repeated, of course, over and over, many times a minute, and the truck will move into the mine with its load. When it reaches a jack arranged as above described, the arm 71 will engage the abutment 72 and the intermittent grip devices will be forced to released position, and held released. The latch 77 will prevent the truck from running back away from the jack. The side covers of the compartments can then be opened and the load discharged. When it is desired to have the vehicle travel out of the mine, it is simply necessary to unhook the latch 77 and the vehicle will promptly travel outwardly as above described.

From what has been said above, it will be evident that I have provided a very effective conveyor-propelled supply truck—one which requires the establishment of a gripping relation with the pan line only during movement in one direction; one which can be rendered operative or inoperative at will in a very simple manner; one which has its propulsive effort terminated automatically on reaching a desired position; and

one which is prevented by latch means associated therewith from starting back away from the face prior to the positive unlatching thereof.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, a shaker conveyor trough having flanged side walls, a car adapted to traverse the conveyor trough and having wheels for riding on said walls, and intermittent grip devices co-acting with the flanges of said side walls for effecting movement of said car along said conveyor trough including shoes arranged beneath at least some of said wheels, links pivotally connected to said shoes and pivotable about the axes of said wheels, resilient means for yieldingly moving said shoes to positions with said links at an angle to the vertical and said shoes in contact with said flanges, and means for at will moving said shoes to position their pivots vertically beneath the axes of pivotal movement of said links including a toggle mechanism positioned to react on said car and against said resilient means.

2. In combination, a conveyor trough having side walls, a car adapted to traverse the conveyor trough and having wheels for riding on said side walls, and material storage compartments at the outer sides of said walls and extending below the tops thereof.

3. In combination, a shaker conveyor trough having flanged side walls, a car adapted to traverse the conveyor trough and having wheels for riding on said walls, at least one intermittent grip device co-acting with one of the flanges of said side walls for effecting movement of said car along said trough, resilient means for thrusting said intermittent grip device into gripping relation to said flange, and means engageable, as said car traverses said trough by an extraneous

ous stationary abutment for overcoming said resilient means and moving said intermittent grip device to an inoperative position.

4. In combination, a shaker conveyor trough having flanged side walls, a car adapted to traverse the conveyor trough and having wheels for riding on said walls, intermittent grip devices co-acting with the flanges of said side walls for effecting movement of said car along said trough, toggle controlled resilient means for effecting gripping operation of said intermittent grip devices, and means engageable with an extraneous abutment for overcoming said resilient means and permitting said toggle to move to locked position for interrupting the operation of said intermittent grip devices.

5. In combination, a shaker conveyor trough having flanged side walls, a car adapted to traverse the conveyor trough and having wheels for riding on said walls, intermittent grip devices co-acting with the flanges of said side walls for effecting the movement of said car along said conveyor trough, means engageable, when said car attains to a predetermined position along said trough, by an extraneous element relative to which said car is movable along said trough, for rendering said intermittent grip devices inoperative, and means also engageable with an extraneous element relative to which said car is movable along said trough, for holding said car against retrograde movement when said intermittent grip devices are rendered inoperative.
